UNITED STATES PATENT OFFICE.

ALBERT D. LEVY, OF CLEVELAND, OHIO.

DESIGN FOR A FAUCET-HANDLE.

SPECIFICATION forming part of Design No. 32,495, dated April 10, 1900.

Application filed September 23, 1899. Serial No. 731,492. Term of patent 7 years.

To all whom it may concern:

Be it known that I, ALBERT D. LEVY, a citizen of the United States of America, residing at Cleveland, county of Cuyahoga, and State 5 of Ohio, have invented and produced a new and original Design for a Faucet-Handle, of which the following is a specification, reference being had to the accompanying drawing, that forms a part thereof and shows a side 10 elevation of a faucet embodying my new design.

My design for a faucet-handle, as shown in the drawing, comprises a head e, that 15 composes the central portion of the handle and has two arms f and f, arranged at opposite sides, respectively, of the head and projecting laterally in opposite directions, respectively. Each arm f has a ball-shaped outer 20 end g and has two reversely-arranged conical portions h and i, arranged with their larger portions adjacent to each other and arranged, furthermore, in line between the said end g and the head e and uniform or approximately uniform in dimensions.

The essential or characteristic feature of 25 my design for a faucet-handle consists, therefore, in the two reversely-arranged cones h and i, formed upon each arm f of the head e, with the outer cone of each arm terminating at its smaller end in a ball-shaped member g 30 and with the smaller end of the inner cone of each arm terminating in the head e.

What I claim is—

The design for a faucet-handle, substantially as herein shown and described. 35

Signed by me at Cleveland, Ohio, this 7th day of September, 1899.

ALBERT D. LEVY.
